UNITED STATES PATENT OFFICE.

JOHN H. LONSKEY, OF YPSILANTI, MICHIGAN, ASSIGNOR TO CENTRAL SPECIALTY COMPANY, OF DETROIT, MICHIGAN, A CORPORATION OF MICHIGAN.

SOIL-PIPE FITTING.

Application filed January 15, 1923. Serial No. 612,745.

The invention relates to soil pipe fittings and refers more particularly to closet bends. The main object of the invention is the provision of a conduit provided with recesses 5 in its outer surface for engagement in by the means for securing a cover to an end of the conduit. Another object is the provision of means upon the cover for directing the securing means into the recesses when 10 tightening the cover in place. With these as well as other objects in view, the invention resides in the novel features of construction and combinations and arrangements of parts as more fully hereinafter set 15 forth.

In the drawings:

Figure 1 is a perspective view of a closet bend and a separated cover which embody my invention;

Figure 2 is a central cross section therethrough.

As shown in the present instance, my invention is applied to closet bend each of which, upon the removal of the temporary 25 or testing cover, is engageable by the closet flange and also by the closet bowl flange, the former engaging over the inlet end of the bend and the latter engaging in the inlet end. With my construction, the temporary or testing cover is detachably secured 30 to the closet bend in such a way that the bend does not subsequently interfere with the assembly of the closet flange or closet bowl flange. Furthermore, both the cover 35 and bend may be cheaply manufactured and readily secured together.

As shown, 1 is the closet bend and 2 the temporary or testing cover which is adapted to be applied to the inlet end of the bend 40 to close the same. The closet bend has the plurality of peripherally spaced recesses 3 in the outer surface of its inlet end, these recesses progressively increasing in depth from their lower to their upper ends and 45 forming shoulders 4 at their upper ends. The cover 2 is of a diameter to fit over the inlet end of the bend and has the depending annular flange 5 for engaging the inner wall thereof to position the cover upon the bend. 50 6 is a suitable gasket preferably formed of rubber and located between the cover near its periphery and the end of the bend for sealing the joint therebetween.

For detachably securing the cover to the

bend, I have provided the stove bolts 7 loosely engaging in openings 8 formed in the peripherally spaced projections 9 upon the cover. The slotted heads 10 of these stove bolts are adapted to engage in the recesses 3 and abut against the shoulders 4 upon the tightening of the nuts 11 whereby the cover may be firmly held in place and the gasket placed under compression to seal the joint between the cover and the bend. To guide the heads 10 into the recesses 3, the projections 9 upon the cover each have the depending flange 12, the inner face 13 of which is inclined to extend substantially parallel to the vertical face of the recess, the arrangement being such that as the stove 70 bolt head is drawn upwardly, it will be positively forced into its recess and finally abut the shoulder at the upper end of the recess.

From the above description, it will be 75 readily seen that I have provided a simple construction of closet bend which may be manufactured at a cost as low as the cost of manufacture of the bends ordinarily used. Also, that the shoulders formed upon this 80 bend for cooperating with the members for securing the temporary or testing cover to the bend are located so that they will not interfere with the subsequent assembly of the closet bend flange or of the closet bowl 85 upon the bend. Furthermore, that I have provided means for guiding the heads of the threaded securing members into the recesses formed in the bend.

What I claim as my invention is:

1. The combination with a closet bend having peripherally spaced recesses in its outer surface at its inlet end, of a cover for the inlet end, means engaging said cover and recesses for securing said cover to said bend, and depending flanges upon said cover having inclined surfaces extending inwardly for guiding said securing means inwardly into said recesses.

2. The combination with a closet bend and a plurality of peripherally spaced recesses in its outer surface at its inlet end, said recesses progressively increasing in depth toward the inlet end, of a cover for the inlet end, threaded members movable transversely of said cover and having heads engageable in said recesses for securing said cover to said bend, and depending flanges

- upon said cover engageable with said heads for guiding the same into said recesses, said flanges being inclined in the same direction as the bottom surfaces of said recesses.
5. The combination with a cylindrical member having a recess in its outer surface forming a clamping shoulder, said recess progressively increasing in depth toward said shoulder, a cover for closing said cylindrical member, a clamping screw engageable with said cover, and a head upon said clamping screw, said cover being provided with an inwardly inclined surface engageable with said head for forcing the same into 15 said recess.
10. The combination with a cylindrical conduit having a plurality of peripherally spaced recesses formed in its outer surface, said recesses progressively increasing in depth and forming shoulders at the deepest ends thereof, a cover for closing said cylindrical member, clamping bolts engageable with said cover, rounded heads upon said bolts engageable in said recesses, and lugs 20 upon said cover plate having inwardly in-
- clined surfaces substantially parallel to the bottom surfaces of said recesses.
15. The combination with a cylindrical member having a recess in its outer surface forming a clamping shoulder, said recess progressively increasing in depth toward said shoulder, a covering for said cylindrical member, clamping means secured to said cover having a portion engageable in said recess, and an inwardly inclined flange upon 25 said cover engageable with said portion to force the same into said recess.
20. The combination with a cylindrical member, and a cover therefor, of clamping means secured to said cover and adapted to 30 engage shoulders in said cylindrical member, said shoulders being formed by recesses in said cylindrical member progressively increasing in depth toward said shoulder, and inwardly inclined depending flanges upon 35 said cover engageable with said clamping means for forcing the same into said recesses.

In testimony whereof I affix my signature.
JOHN H. LONSKEY.
